UNITED STATES PATENT OFFICE.

HUBERT M. PERRY, OF CHICAGO, ILLINOIS, ASSIGNOR TO SOPHIE L. WOODS, OF CHICAGO, ILLINOIS.

SIDE BEARING FOR RAILWAY CARS.

Application filed January 28, 1924. Serial No. 638,904.

This invention relates to improvements in side bearings for railway cars and consists of the matters hereinafter described and more particularly pointed out in the appended claim.

The invention is addressed to the type of truck side bearing known as a counterbalance or gravity centering bearing. Such bearing comprises an open box-like casing 10 with a bearing plate in the bottom and a roller adapted to roll on said bearing plate,—said roller being overweighted on one side so that when released from load,—that is to say when disengaged from bearing 15 engagement with the opposed bearing plate on the body bolster—it will be returned by gravity to a central position in the casing, being guided thereto by interengaging lugs and recesses provided respectively on the 20 roller and in the side walls of the casing.

While the action of gravity on the roller alone will act to return it to central position, this movement of the roller is apt to be sluggish in bearings as heretofore made, 25 particularly when cinders and dust accumulate in the casing, and the object of the present invention is to provide additional means coacting with the overweighted roller to increase its tendency towards, and speed 30 up its movement when released from load in its return to, the center of the casing.

The advantages of the invention will appear more clearly as I proceed with my specification.

In the drawings:—

Fig. 1 represents a top plan view of the improved bearing, one end wall of the casing being partly broken away.

Fig. 2 is a view representing a side elevation partly in longitudinal central section.

Fig. 3 is a view representing a transverse section through the bearing in a plane indicated by the line 3—3 of Fig. 2.

Fig. 4 is a sectional view similar to the sectional part of the view shown in Fig. 2, showing a somewhat modified form of the bearing.

Referring now to that embodiment of the 50 invention illustrated in the drawings and particularly in Figs. 1 to 3 thereof:—10 indicates the casing, which is a rectangular open top frame having side walls 11, 11 and

end walls 12, 12 with integral laterally extending ears or lugs 13, 13 for securing it 55 to the truck bolster. The bottom of the casing is closed by a filler plate 14 upon which rests a bearing or wear plate 15. Both of these plates are insertable in the bottom of the casing from below in a familiar manner 60 and are held therein by bendable flanges 16 at the ends of the opening in the bottom of the casing, and against shoulders 17 in the side walls of the casing which engage the top wall of the bearing plate. The 65 bearing plate 15 rises from the middle of the casing towards each end, having as shown, a curved top surface 18.

19 indicates the antifriction member or roller. Said roller is wide at the bottom 70 and narrow at the top, the bottom bearing surface 20 being made on a large radius and the top bearing surface 21 being made on a smaller radius. This provides an ample 75 overweight for the roller so that its tendency will always be to return to a position with its longest median line in vertical position. In the side walls of the casing are provided V-shaped recesses 22 and the antifriction roller has lugs 23 at its end engaged 80 in said recesses,—the sides of the recesses and the lateral edges of the lugs being so formed and proportioned relative to the contemplated movement of the antifriction roller from its central position to the predetermined limit of its movement toward either 85 end of the casing that they will guide the roller in its movement and hold it against bodily shifting on the bearing plate under 90 end jars or shocks to the casing.

It will be manifest from a consideration of Fig. 2 that when the roller, by the engagement of the opposed bolster bearing plate (indicated at 24) with its top side, has been rotated to one end of the casing, 95 as indicated in dotted lines, a release of the roller by the bolster bearing plate will permit the roller to roll down the inclined bearing plate towards the middle of the casing. This rolling movement is brought about not only by the overweight of the roller due to its formation but also by the inclination of the bearing plate down which it rolls. Thus, a quick and rapid return of the roller to its central position is assured. 100

The greatest width of the lugs 23 is made 105

at right angles to the greatest diameter of the roller, so that the roller will not only always return to its central position, but its greatest diameter will be returned to central position in the casing in a vertical position.

As will be readily understood, the roller will tend to increase the distance between the truck and body bolster as it rolls from central position to either end of the casing, 10 as indicated by the full line and the dotted line showing the position of the body bearing plate 24. But manifestly, if such lifting of the body bolster is undesirable and the body and truck bolsters are intended to be 15 maintained in parallel relation during the bearing engagement of the antifriction device, this result may be readily produced by so forming the top bearing surface of the roller, as indicated at 21* in Fig. 4, that the 20 rise of the roller due to the upward inclination of the bearing plate 15, will be compensated for. That is to say, said top bearing surface is so curved with reference to the curvature of the bottom bearing surface, 25 that the vertical distance between the bearing points at top and bottom of the roller in the plane of the load, as indicated by the line 25 at the center of the casing, will decrease as it approaches the end of the casing 30 in proportion to the rise of the bearing

plate, as indicated by the line 25*, with the roller at the end of the casing.

While in describing my invention I have referred to several details of mechanical construction and arrangement of parts, it is to be understood that the invention is not limited thereto except as may be pointed out in the appended claim.

I claim as my invention:

In a side bearing for railroad cars, an open top casing, a bearing plate in said casing inclined from the middle of the casing upwardly towards the ends of the casing, an antifriction roller capable of rolling movement on said bearing plate, said roller being 40 in cross section wide at the bottom and narrow at the top, the top and bottom bearing surface of said roller being so formed that the distance between the top and bottom bearing points of the roller on the load line 45 as the roller assumes different positions in its rolling movement towards the end of the casing is diminished in proportion to the rise of the bearing plate, and interengaging parts on said roller and said casing to guide 50 the roller in its rolling movement.

In testimony that I claim the foregoing as my invention, I affix my signature, this 23d day of January A. D. 1924.

HUBERT M. PERRY.
